UNITED STATES PATENT OFFICE.

WILLIAM A. WRIGHT, OF CENTRETON, NEW JERSEY, ASSIGNOR OF TWO-THIRDS TO JOSEPH B. DE YOUNG AND CHARLES Z. DE YOUNG, OF PHILADELPHIA, PENNSYLVANIA.

DISINTEGRATING CORN-HUSKS.

SPECIFICATION forming part of Letters Patent No. 234,641, dated November 16, 1880.

Application filed August 19, 1880. (No model.)

To all whom it may concern:

Be it known that I, WILLIAM A. WRIGHT, a citizen of the United States, residing at Centreton, in the county of Burlington, State of New Jersey, have invented a new and useful Improvement in Disintegrating Corn-Husks, which improvement is fully set forth in the following specification.

My invention consists of a method of disintegrating corn-husks whereby I produce a long, uniform, and valuable staple of the natural state of the husks.

In carrying out my invention I proceed as follows: After the corn is shucked the husks, with end stub attached, are dampened by being immersed in or sprinkled with water or steam, so as to be softened and made pliable for subsequent manipulations. The husks as thus treated are then placed on a suitable bed or table and subjected to the action of a rotary or sliding comb, the effect whereof is to slice the husks and produce long and uniform shreds. The stub is then severed, thus separating the several shred-leaves of the husks.

It is not essential to use husks connected by their stubs; but such are desirable, as they are more readily handled and manipulated.

It will be seen that by this method of dis-

integrating corn-husks I utilize the entire body of each leaf, fiber, and integument, the loss—³⁰ little pieces in the form of chips—being slight, the shreds being both fiber and integument, and so obtain a staple which is long, fine, soft, uniform, and solid, and serviceable for many purposes.

Suitable machinery for carrying out with ease and rapidity this invention forms the subject-matter of other applications for Letters Patent.

Having thus described my invention, what I claim as new, and desire to secure by Letters Patent, is—

1. The method of disintegrating corn-husks, consisting in dampening the husks in their natural state and then combing them in such state, ⁴⁵ thus producing a staple with both fiber and integument preserved, substantially as and for the purpose set forth.

2. Staple formed of disintegrated corn-husks in their natural state, having the fiber and integument preserved, substantially as and for the purpose set forth.

WM. A. WRIGHT.
